UNITED STATES PATENT OFFICE.

LOUIS S. IRGENS, OF VALLEY CITY, NORTH DAKOTA.

DESIGN FOR A STOVEPIPE-DRUM.

SPECIFICATION forming part of Design No. 31,870, dated November 21, 1899.

Application filed October 20, 1899. Serial No. 734,266. Term of patent 14 years.

To all whom it may concern:

Be it known that I, LOUIS STEAVEN IRGENS, of Valley City, in the county of Barnes and State of North Dakota, have invented and 5 produced a new and original Design for a Stovepipe-Drum, of which the following is a full, clear, and exact description.

Reference is to be had to the accompanying drawings, forming a part of this specification, 10 in which similar characters of reference indicate corresponding parts in both the views.

Figure 1 is a plan view of a stovepipe-drum, showing my design; and Fig. 2 is a side elevation of the same.

15 The design in its entirety consists of a shell A and internal tubes B, appearing transversely and diametrically of the shell, one

above the other in spiral form, the ends of the tubes being at the peripheral surface of the shell and the upper end A' of the shell 20 appearing slightly contracted and corrugated.

The leading feature of the design consists of the shell having the spirally-arranged tubes, as shown.

Having thus fully described my invention, 25 I claim as new and desire to secure by Letters Patent—

The design for a stovepipe-drum as herein shown and described.

LOUIS S. IRGENS.
